FILM MARKING APPARATUS

Albert W. Tondreau, Glendale, Calif., assignor
to Warner Bros. Pictures, Inc., New York,
N. Y., a corporation of Delaware

Application November 12, 1938, Serial No. 239,942

6 Claims. (Cl. 95—75)

This invention relates to film marking apparatus and has particular reference to apparatus for printing identification marks on motion picture film.

In printing motion picture film, especially the sound track thereof, very critical adjustment of the printing machines is necessary in order to obtain best results. The slightest amount of loose play or misalignment in any of the various film driving or guiding elements of the printing machines, as well as the optical systems therefor, may be sufficient to cause relative misalignment between the light sensitive film being printed and the developed printing film with consequent distortion of the images being printed.

Furthermore, due to wear, vibration, etc., frequent readjustment and repair are necessary to maintain the printing machines in correct adjustment. The identity of the particular printing machine requiring such adjustment or repair is frequently lost since the film, after being printed, is generally first developed, in the case of printed sound track, and is thereafter run through a sound reproducer before the need for such adjustment or repair is noticed. Heretofore, the identification of the particular printing machine employed to print a certain strip of film was obtained by allocating a different number or symbol to each machine and having the operator mark at the beginning or end of that strip the particular number or symbol for that machine. This was not entirely satisfactory because of the tendency of the operator to forget to place such identification mark on the film. Further, since the various separately printed film strips are often inter-cut with each other, or portions thereof deleted, the above identification marks are often lost.

The present invention overcomes the above mentioned defects by automatically exposing identification marks on a film strip simultaneously with the printing of the film images thereon. These identification marks are exposed at short, regularly spaced intervals whereby sections of the film strip may be either inter-cut with other film strip sections or deleted entirely without losing the identification of the particular printing machine employed to print the same.

The invention is also useful in other relations for marking film.

For details of the invention, reference may be had to the accompanying drawing wherein:

Fig. 1 is a sectional plan view through a printing machine embodying the present invention.

Fig. 2 is a transverse sectional view through the printing machine and is taken along the line 2—2 of Fig. 1.

Fig. 3 is an enlarged, fragmentary, sectional view through the optical system for printing the sound track and identification marks on a film and is taken along the line 3—3 of Fig. 2.

Fig. 4 is a fragmentary view of the film drum showing the identification mark printing apertures.

Fig. 5 is a fragmentary, sectional view of the optical system of an alternate form of identification printing device.

Referring in particular to Figs. 1 and 2, the invention is shown as being incorporated in a sound track printing machine wherein a developed motion picture film 10 having a sound track thereon (with or without picture images) and a light sensitive film 11 are run in contact with each other over a hollow printing drum 12 or sprocket generally indicated at 12. Drum 12 comprises a disc member 13 integrally formed on a shaft 14 and having a series of spaced film engaging sprocket teeth 15 around the edge thereof. An annular flange 16 is secured to the member 13 by screws 16' to support the picture portion of the films traveling thereover. The flange 16 extends across the entire picture portion of the films and terminates at the inner edge of the sound track of film 10.

Shaft 14 is journaled in a bearing member 17 mounted in a bore 18 formed transversely through the printer casing 19, and is continuously driven in a suitable manner from a printer motor (not shown).

The sprocket perforation edges of the two films 10 and 11 adjacent the sound track portions thereof are supported by a stationary annular guide member 21 secured within the bore 18 by screws 22. The film guiding periphery of the guide member 21 is of the same diameter as that of the flange 16. The edge of guide member 21, adjacent the outer edge of the flange 16 extends to the outer edge of the sound track of film 10. Thus the drum 12 and guide member 21 restrict any light passing therebetween to the sound track area of the film 10.

As shown in Fig. 2, the film 10, after passing from a supply reel and feed sprocket (not shown) is passed over a guide roller 23, thence over a guide plate 24 secured to the printer casing 19 in an opening 26. Plate 24 is tangentially aligned with the periphery of drum 12. Film 10 thence passes onto the aligned peripheries of drum 12 and member 21. On leaving the drum 12 and

member 21, the film 10 passes over a second guide plate 25 secured to the printing casing 19 in opening 28.

The light sensitive film 11 after passing from a supply reel and feed sprocket (not shown) is passed over a guide roller 27 and thence in contact with the developed film 10 while passing over the drum 12. The rollers 23 and 27 have edge flanges thereon to separately edge guide the films 10 and 11, respectively. The two films 10 and 11 pass in contact over both the guide plate 25 and a guide roller 28, and thereafter are drawn by suitable sprockets (not shown) onto respective film take-up reels.

15 Suitable means not shown may be provided to maintain a constant tension in the two films 10 and 11 during their passage over the drum 12 to maintain the same in an intimate contact at the printing point during the printing operation.

To further obtain an intimate contact between the films 10 and 11 at the printing point a pad roller 38 is provided directly opposite the printing point. Roller 38 rides on the film 11 over both the flange 16 of drum 12 and the film guiding periphery of member 21. Roller 38 is rotatably mounted in a self-aligning mount generally indicated at 31 which is mounted on a transversely extending shaft 32 for movement about a horizontal axis. The roller 38 is urged against the film 11 by a tension spring 33 intermediate the upper end of a rod 34, forming part of the mount 31, and a projection extending upwardly from a gate member 35. Gate member 35 is pivotally mounted by means of a pin 36 to the casing 19, permitting the same, including the roller 38, to be moved away from the film 11 for threading purposes. A snap-over spring arrangement 37 connected between a depending lug 38 on gate member 35 and a stationary support (not shown) on the casing 19 is provided to hold the gate member 35 in either open or closed position.

The sound track of the film 10 is printed on the film 11 by an optical system comprising generally a cylindrical optical assembly tube 39. A printing lamp 40 mounted in an enclosed lamp housing 41 is carried at one end of tube 39.

The tube 39 is mounted for transverse and rotatable movement in an end cover plate 42 enclosing the bore 48. Plate 42 is secured to the printing casing 19 by bolts 43 and 43' extending through elongated parallel slots 44 and 44', respectively, in the plate 42 and are threaded in the casing 19. By loosening the screws 43 and 43' the end plate 42 and tube 39 carrying lamp 40 may be transversely adjusted. The tube 39 is slidably mounted in a bushing 45 secured in an opening formed in the end plate 42 permitting tube 39 to be adjusted longitudinally and rotatably. A set screw 46 threaded in bushing 45 and adapted to bear against the tube 39 is provided to lock tube 39 in any desired position.

65 Referring to Fig. 3, the optical system of tube 39 comprises, in addition to a slit member and condenser lens (not shown) a color filter 48 and a pair of objective lenses 49. Lenses 49 are mounted in a forward extension 39' of tube 39. A right angle prism 50 carried by a prism mount 51 is supported in front of the objective lens 49 to deflect the slit of light projected by the lens 49 at right angles onto the sound track of film 10. Prism mount 51 has a bore extending there- 75 through and fitted over the reduced cylindrical

end portion 52 of the lens tube extension 39', thus permitting the prism 50 to be rotatably adjusted and/or laterally adjusted in a direction parallel to the optical axis of tube 39. A set screw 53, threaded in mount 51, is provided to lock 5 the mount 51 in any desired position. The prism 50 is clamped on the mount 51 by a lamp supporting member 54 through screws 55 which extend through member 54 and are threadably mounted in apertures formed in projections 56 10 formed integrally with the lens mount 51 and extending on opposite sides of the prism 50. Member 54 has a bore therein through which extends a cylindrical light tube 58. Light tube 58 has a conical downwardly extending section 15 51, extending therefrom and opening opposite the path of travel of an aperture or notch 57 formed in drum 12. Aperture 57 is coextensive with one or more radially extending holes 58 opening into the outer periphery of drum 12 in intermediate adjacent sprocket teeth 18 as shown in Fig. 4. These holes 58 may be of different shapes, or, if desired, may be in the form of numbers or letters. A small lamp 59 is provided in a socket member 60 mounted in the tube 58 25 and insulated therefrom by an insulating sleeve 61. Thus, it will be seen that the tube 58 and extension 51 thereof serve to convey light from lamp 59 to the aperture 57 while preventing any light therefrom from striking the films 10 30 and 11 intermediate the adjacent edges of the drum 12 and guide member 21.

An electric terminal 62 is grounded to the socket member 60 and is connected by a conductor 63 to a suitable source of current. A second electric terminal 64 insulated from the socket 35 60 by an insulating sleeve 65 and washer 66 contacts the end terminal of lamp 59 and is also connected to the source of current by conductor 66. Conductors 63 and 66 extend through 40 an aperture 57 (Fig. 1) in the end plate 42.

A set screw 68 is threaded through the lamp supporting member 54 and bears against the tube 58 to clamp the same in any adjusted position. Due to the thinness of the walls of both 45 the tube 58 and insulating sleeve 61, the set screw 68 also serves to lock the socket member 60 in any adjusted position within the tube 58.

In adjusting the optical system, the set screw 46 is first loosened to permit the tube 39 to be 50 moved longitudinally to correctly align the beam of light deflected by prism 50 onto the film 10. The tube 39 may also be rotatably adjusted to position the printing point, determined by the printing beam, directly in line with the pad roller 55 38. Thereafter, the bolts 43 and 43' are loosened to permit the end plate and tube 39 to be adjusted transversely to correctly focus the light beam from lamp 40 on the contacting surfaces of films 10 and 11. The set screw 68 in lamp 60 supporting member 54 is then unloosened to permit the tube 58 to be correctly aligned relative to the opening 57 and inner surfaces of drum 12. Furthermore, while screw 68 is released, the socket member 60 may be adjusted to correctly 65 align lamp 59 relative to the light passage in tube 58 and the extension 51 thereof.

It will be seen from the above description that, while the sound track is being continuously printed on the film 11, identification marks defined by the apertures 58 opening between the sprocket teeth 18 will be printed onto the film 11 intermediate the sprocket perforations thereof at regularly spaced intervals, the spacing of which is determined by the circumference of 75

drum 12. It should be borne in mind that a negative film as at 10 is generally transparent intermediate the sprocket perforations, thereby permitting the identification marks to be printed therethrough onto the light sensitive film 11.

By varying the number of apertures 58 or the cross sectional shapes thereof in different printing machines, the particular printing machine employed to print a certain strip of film may be readily determined on inspection of the film after it is developed. Furthermore, since these identification marks are printed along the film at regularly spaced short intervals, i. e., twelve inches apart, the film may be intercut with other strips of film, or portions of that strip may be deleted without losing the identification of the particular printing machine employed to print the same.

An alternate form of identification mark fogging device adapted to be employed in the printer above described, is illustrated in Fig. 5. In this case, the prism 50' is secured upon a mount 51', similar to that of 50, by a flat plate 10. Plate 70 secured to spaced projections, one 25 of which is shown by the dotted lines 56' extending from the mount 51' on opposite sides of prism 50' by screws 71. In this case, a small lamp 72 is mounted in an insulated socket 73 threaded into a tubular member 74. Member 74 30 is securely mounted on the end of a bracket 75 in the form of a metal strip, the other end of bracket 75 being mounted on a block 76 forming part of the optical tube assembly 39a and supporting a filter 48'. The member 74 has a bore 35 77 at the front thereof and in line with lamp 72 to direct a beam of light therefrom. The member 74 is directed downwardly toward the path of movement of one or more apertures 58' extending intermediate the various spaced sprocket 40 teeth 15' in a manner similar to apertures 58 described in connection with Figs. 1 to 4, inclusive. A shield 78 is suitably welded, or otherwise attached to the member 74 to form a light shield to prevent the light projected by the lamp 72 45 from reaching the film 10' at the portion thereof intermediate the inner edges of the drum 12' and the stationary ring member 21'. The edge 79 of shield 78 is formed concentric with the inner surface of the drum 12' and lies closely adjacent thereto so as to reduce the amount of light passing therebetween or, at least to restrict any light passing therebetween in a path away from the surface of film 10' extending over the opening adjacent edges of drum 12' and guide ring member 21'.

The use of the identification marking feature of the invention as applied to a contact printer is disclosed and claimed in my co-pending application Serial No. 230,523, filed September 17, 60 1938 for "Contact printer" of which my present application is a continuation in part.

It will be seen from the above description that the invention provides a simple automatic means of providing printer identification marks on a 65 film being printed. Furthermore, although the invention has been described in its preferred

form in connection with a contact sound track printing machine, it may also be applied to a printing machine for printing either pictures or both pictures and sound track on a motion picture film without departing from the spirit of the appended claims. Also, the broad aspects of the invention may be applied to other motion picture film exposing apparatus wherein a light sensitive film is caused to travel over a rotatable member.

Also, the marks exposed on the film, instead of serving to identify the particular machine handling the film, may serve to indicate any other desired information.

I claim:

1. Film marking apparatus comprising a rotatable member having a cylindrical flanged portion open at one end thereof and adapted to support a film with a portion thereof overhanging said flanged portion, means for rotatably supporting said member for rotation about the axis of said cylindrical portion, said member having an aperture therein, means for directing a beam of light through said aperture from within said flanged portion to the film, and means for preventing said light from striking said overhanging portion of said film. 20

2. Film marking apparatus according to claim 1 comprising sprocket teeth on said member, said aperture forming an opening on the periphery of 30 said member intermediate two of said sprocket teeth.

3. Film marking apparatus comprising a rotatable member having a cylindrical flanged portion adapted to support a film with a portion thereof overhanging said flanged portion, means for rotatably supporting said member for rotation about the axis of said cylindrical portion and means associated with said cylindrical portion for exposing an identification mark on the edge 40 of the film from within said flanged portion and means preventing exposure of said overhanging portion of said film from said last mentioned means. 35

4. Film marking apparatus comprising a rotatable hollow film guiding member adapted to support a light sensitive film on the periphery thereof with a portion of said film overhanging said member, said member having an aperture communicating the interior thereof with the 50 periphery thereof, a tubular member having a light transmitting passage therein, said member extending within said interior of said film guiding member, a lamp in said tubular member, and means whereby said tubular member may be adjusted to align the passage thereof with the path of movement of said aperture and to prevent light from said lamp from exposing said overhanging portion of said film. 55

5. Film marking apparatus according to claim 4 comprising common means for locking said lamp and said tubular member in position. 60

6. Film marking apparatus according to claim 4 comprising means whereby said lamp may be adjusted in said tubular member. 65

ALBERT W. TONDREAU.
